Fred P. Forman,
ATTORNEY

UNITED STATES PATENT OFFICE.

HENRY HANSEN, OF OLYMPIA, WASHINGTON.

TIMBER-SIZING MACHINE.

1,261,384.

Specification of Letters Patent.

Patented Apr. 2, 1918.

Application filed March 21, 1917. Serial No. 156,251.

To all whom it may concern:

Be it known that I, HENRY HANSEN, a citizen of the United States, residing at Olympia, in the county of Thurston and State of Washington, have invented certain new and useful Improvements in Timber-Sizing Machines, of which the following is a specification.

My invention relates to improvements in timber sizing machines, and has for its principal object to provide an improved and novel type of movable power operated machine for sizing, channeling and otherwise milling heavy timbers for ship construction and the like. A further object of my device is to provide manually operated means for bringing the cutting tools in contact with the wood; to provide detachable guides for fastening to the timber in order to provide a means for retaining the machine in proper relationship to the timber. In ship construction and the like, there are many heavy timbers which must be channeled, rabbeted, chamfered or otherwise milled by hand in order to make them properly fit the ship. This work is usually done by ship carpenters by hand tools and is very expensive, due to the high cost of labor. My machine is designed to obviate much of this hand labor. Other objects will appear as my invention is more fully explained in the following specification, illustrated in the accompanying drawing and pointed out in the appended claims.

In the drawings, Figure 1 is a plan view of my device shown in position on a fragment of timber. Fig. 2 is a side elevation of same. Fig. 3 is an enlarged detail section of one form of guide shown attached to a fragment of timber.

Referring more particularly to the drawings, numeral 1 indicates a timber along either side of which a guide 2 is secured by screws, nails or the like. Guide 2 preferably has a longitudinal channel 3 within which flanges 4 of my machine fit slidably. My machine has a pair of similar side frames 5 to the lower end of which the flanges 4 are secured. The side members 5 are adjustably held in parallel spaced relationship to each other by means of bolts 6 and fillers 7. The side frames 5 are adjusted to properly fit the timber or to fit the width of the cutting tool which it is desired to use. The guides in this particular case are shown attached to the sides of the timber but it is

evident that guides of slightly different shape might be secured directly to the face of timber. Each of the side frames 5 are provided with an upstanding quadrant 8 which has a slot 9. A pair of similar hand levers 10 are revolvably pivoted to one of the bolts 6 and are provided with thumb nuts 11 which coöperate with the slots 9. Setting screws 12 are also pivoted to levers 10 and pass through enlarged openings in lugs 13 which are outstanding from quadrants 8. The lugs 13 are provided with spherical cups which fit a spherical hub 14 of a hand wheel 15. The hand wheels 15 are threaded on to the screws 12 and are used to adjust the levers 10. A shaft 16 is revolvably mounted in the lower ends of levers 10 and is provided with a shanked connection 17 to which a flexible shaft from an air or electric motor may be attached. Any desirable form of revolving tool, such as a channeler 18, may be secured to shaft 16. The operation of my device is as follows: After the guides have been secured to the timber 1 the machine is positioned with the flanges 4 in the channels 5 and the hand levers are set so that the cutting tool 18 is in contact with the top of the timber. The entire device is then either shoved forward manually or if the tool revolves forwardly, the device will be self propelling and will only need an operator to control its speed and movement.

While I have shown a particular form of embodiment of my invention, I am aware that many minor changes therein will readily suggest themselves to others skilled in the art without departing from the spirit and scope of the invention, and I therefore desire to avoid being limited to the exact form shown and described.

Having described my invention, what I claim as new and desire to protect by Letters Patent, is—

1. In a device of the class described, the combination of a pair of similar side frames, adjustable guides within which the said side frames are slidably mounted, levers adjustably pivoted to said side frames, and a power operated tool revolvably mounted on the lower ends of said levers.

2. In a device of the class described, the combination of a pair of similar side frames having parallel outstanding flanges, means for adjusting the position of the said side frames with respect to each other, a pair of channeled guides which coöperate with the

- said flanges, a pair of similar hand levers pivotally mounted between the said side frames, a power operated tool shaft, revolvably mounted within the ends of said levers, and means for adjusting the position of said levers, whereby a tool placed upon the tool shaft may be brought into contact with a timber upon which the said guides are mounted.
10. 3. In a device of the class described, the combination of a pair of similar side frames having parallel outstanding flanges, means for adjusting the position of the said side frames with respect to each other, a pair of 15 channeled guides which coöperate with the said flanges, a pair of similar hand levers pivotally mounted between the said side

frames, a power operated tool shaft revolvably mounted within the ends of said levers, and means for adjusting the position of said levers, said means including; quadrants integral with the said side frames, screw rods pivotally mounted to each of said levers, spherically faced lugs outstanding from said quadrants, and spherically hubbed hand wheels mounted between said lugs and in threaded coöperation with the said screws.

In testimony whereof I affix my signature in the presence of two witnesses.

HENRY HANSEN.

Witnesses:
